[57] CLAIM

The ornamental design for a bicycle alarm, as shown and described.

DESCRIPTION

FIG. 1 is a side elevational view of the bicycle alarm showing our new design, the bicycle being shown in broken lines for illustrative purposes only;

FIG. 2 is a right hand end view thereof on an enlarged scale;

FIG. 3 is a front elevational view thereof on an enlarged scale;

FIG. 4 is a left hand end view thereof on an enlarged scale;

FIG. 5 is a rear elevational view thereof on an enlarged scale;

FIG. 6 is a top plan view thereof on an enlarged scale, the view having been rotated 180° from the positions shown in FIGS. 1-5; and

FIG. 7 is a bottom plan view thereof on an enlarged scale and taken from the same position as shown in FIG. 6.
